CLAIM

The ornamental design for a vehicle steering wheel cover, as shown and described.

DESCRIPTION

FIG. 1 is a bottom view of the vehicle steering wheel cover showing our new design; A top view of the vehicle steering wheel cover is identical to the bottom view as shown in FIG. 1.

FIG. 2 is a side view of the vehicle steering wheel cover illustrating the new design; An opposite side view of the vehicle steering wheel cover is identical to the side view as shown in FIG. 2.

FIG. 3 is a perspective view of the vehicle steering wheel cover shown mounted on a vehicle steering wheel. The vehicle steering wheel is shown in broken lines and is for illustrative purposes only and form no part of the claimed design; and,

FIG. 4 is an enlarged view of a portion of the vehicle steering wheel cover as shown in FIG. 2.
